ELECTRIC PENCIL SHARPENER

Kenneth R. Blake, Detroit, Mich., assignor of
sixty per cent to Earl W. Parrish, and forty per
cent to Fred D. Healy, both of Detroit, Mich.

Application August 26, 1937, Serial No. 161,097

5 Claims. (Cl. 120—96)

This invention relates to sharpener constructions, and particularly relates to improved electrically operated pencil sharpener constructions.

One of the primary objects of the present invention is to provide an improved pencil sharpener structure which properly and efficiently sharpens the end of the pencil and which is simple in construction and economical to manufacture.

10 Another object of the present invention is to provide a motor driven pencil sharpener having gearing associated therewith in which the gearing is effectively sealed against the inclusion of dust, shavings, dirt, or the like, from the sharpening elements.

15 A further object is to provide an improved arrangement of the gears which form the operating mechanism for the sharpener elements by which an efficient and effective pencil sharpener structure is provided.

20 A further object is to provide an improved structure by which bulging of the tip of the pencil being sharpened is prevented.

25 Other objects of the invention will become apparent from the following specification, the drawings relating thereto, and from the claims hereinafter set forth.

30 In the drawing in which like numerals are used to designate like parts in the several views throughout:

Figure 1 is a vertical cross-sectional view of a pencil sharpener structure embodying features of the present invention;

Fig. 2 is a cross-sectional view taken substantially along the line 2—2 of Fig. 1;

35 Fig. 3 is a fragmentary top plan view with parts broken away of the structure illustrated in Fig. 1; and

Fig. 4 is a fragmentary elevational view of a modified form of the present invention.

40 Referring to the drawing, and referring particularly to Figs. 1 to 3, a casing 16 having a top portion 18 with diametrically opposed upstanding supporting lugs 20 and 22 is provided. The casing 16 also has an upstanding centrally disposed bearing portion 24 having an opening 26 therethrough, which receives a bearing sleeve 28. The outer surface of the bearing portion 24 is provided with an annular shoulder 30 for a purpose to be hereinafter explained.

45 The bearing 28 receives therethrough an armature shaft 32 of an electric motor 34. The electric motor 34 is mounted within the casing 16 under the top portion 18 and is suitably secured to the casing. A fan element 35 is suit-

ably connected to the armature shaft 32 for rotation therewith for the purpose of cooling the motor 34.

A driving pinion 36 is fixed to the upper end of the armature shaft 32 for rotation therewith. 5 Diametrically opposed driven gears 38 and 40 are mounted on shaft members 42 and 44, respectively, in mesh with the driving pinion 36. An internal gear 46 is mounted on the annular shoulders 30 of the upstanding bearing portion 10 24 of the casing 16, and is fixed relative to the casing 16 by peening out the upper edge of the upstanding bearing portion 24 as indicated at 48. The internal gear 46 is so constructed and arranged as to be in mesh with the driven gears 15 38 and 40.

Sharpener or cutting elements 50 and 52 are secured to the upper ends of the shafts 42 and 44, respectively, for rotation therewith. The sharpening elements 50 and 52 are preferably 20 conical in shape, and have spiral cutting edges 54 formed on the outer surfaces thereof. There are preferably no less than eight nor more than ten cutting edges per inch with the spiral angle of the cutting edges less than 45° for a 15° inclination angle of taper on a pencil to be sharpened. 25

The sharpener elements 50 and 52 are journaled at their upper ends in a substantially U-shaped frame member 56 which has its lower 30 ends secured to a partitioning member 58. The partitioning member 58 is suitably secured to the top edge of an annular housing member 60. The housing member 60 cooperates with the partitioning member 58 and is of such a construction 35 that the gears 36, 38, 40, and 46 are housed therein and sealed against the entrance of foreign material such as shavings, dust, dirt, or the like, from the sharpening elements.

The shafts 42 and 44 are journaled in openings in the partitioning member 58; and washers 62 and 64 are received over the shafts 42 and 44, respectively. The washers 62 and 64 bear against the top surface of the partitioning member 58, and also bear against the under surfaces 45 of their respective sharpener elements 50 and 52. In order to prevent bulging of the point of the pencil being sharpened, the washer 64 is of greater diameter than the washer 62 and is so constructed and arranged that it extends from under its sharpening element 52 to a position 50 under the lower edge of the sharpener element 50 inside the periphery thereof.

In order to further seal the gears from the inclusion of foreign material the housing member 55

60 is provided with two annular bearing portions 61 and 63, the bearing portion 61 bearing against the outer surface of the upstanding bearing portion 24 of the casing 16, and the bearing portion 63 bearing against the top surface of the top portion 18 of the casing 16.

5 A U-shaped supporting member 66 of channel section is secured to the lugs 20 and 22 of the casing 16 and extends upwardly above the frame 56 of the sharpener element. The member 66 is provided with an opening 68 therethrough which receives and supports a tubular pencil receiving guide member 70. A plate member 72 is supported on the top surface of the member 66 and has an opening therethrough which embraces the member 70. A cover 14 cooperates with the plate member 72 and forms a housing within which an automatic switch 76 is mounted. The switch 76 includes a plate-like contact member 78 which is secured by an insulating bracket 80 to the member 72. Another plate-like contact member 82 is fixed to a similar insulating bracket 80. An inwardly projecting feeler 84 of a suitable insulating material 25 extends through an opening 86 in the receiving member 70 in the path of the pencil inserted in the guideway formed by the member 70. Upon insertion of a pencil in the guideway the feeler 84 is forced outwardly making contact between the contact elements 78 and 82 completing the electric circuit in a manner to be described.

30 Lead wires 85 and 87 are electrically connected to the contact members 78 and 82, respectively, extend downwardly through openings in the members 72 and 66, are held within the channel formed by the member 66 and extended downwardly through an opening in the casing member 16. The lead wires 85 and 87 are there suitably connected with the lead wires generally indicated at 88 providing the electric circuit for the motor 34.

35 Upon insertion of a pencil in the guideway 70, the circuit through the contact members 78 and 82 is completed thus completing the motor circuit 40 and causing operation of the armature shaft 32. This causes rotation of the driving pinion 36 which in turn causes rotation of the driven gears 38 and 40 thus rotating the sharpening elements 50 and 52 about their respective axes. As the gears 38 and 40 are in mesh with the fixed internal gear 46 the sharpening elements 50 and 52 with the frame member 56 plus the housing formed by the partitioning member 58 and the annular member 60 are all caused to rotate about a substantially central longitudinal axis.

45 A cover 90 may be provided which is supported upon an annular shoulder 92 on the casing 16 for enclosing the operating and sharpening structure.

50 Referring to Fig. 4, a modified structure is illustrated in which a single sharpening element 50 is provided which cooperates with an idle blank element 94 to sharpen a pencil inserted in the guideway 70. In this embodiment the driven gear 40 as described above may be dispensed with and the idle blank 94 be permitted to rotate with the shaft 44. The sharpening element 50 serves to properly position and guide the pencil being sharpened to eliminate stalling which would result in the absence of the idle blank 94.

55 Formal changes may be made in the specific embodiment of the invention described without departing from the spirit and substance of the invention, the scope of which is commensurate with the appended claims.

What is claimed is:

1. In a pencil sharpener, a casing, a motor mounted within said casing, said motor having an armature shaft extending outwardly of said casing, a driving gear secured to the outwardly extending end of said armature shaft for rotation therewith, said driving gear meshing with oppositely disposed driven gears, a shaft fixed to each of said driven gears for rotation therewith, a sharpener element fixed to each of said driven gear shafts for rotation therewith, an internal gear meshing with said driven gears and fixed relative to said casing, a plate member serving to journal said driven gear shafts, and an annular member cooperating with said plate member to form a housing which serves to seal said gears against the entrance of dirt from said sharpener element.

2. In a pencil sharpener, a casing, a motor mounted within said casing, said motor having an armature shaft extending outwardly of said casing, a driving gear secured to the outwardly extending end of said armature shaft for rotation therewith, said driving gear meshing with oppositely disposed driven gears, a shaft fixed to each of said driven gears for rotation therewith, sharpener elements each fixed at one of its ends to one of said driven gear shafts for rotation therewith, an internal gear meshing with said driven gears and fixed relative to said casing, a supporting frame member having the other ends of said sharpener elements journaled therein, said frame member being connected to a lower annular member bearing against said casing and being rotatable relative thereto, a plate member fixed to said frame member serving to journal said driven gear shafts, the construction and arrangement of said plate member relative to the annular member and to said gears being such as to enclose and seal said gears against the entrance of dirt from said sharpener element.

3. In a pencil sharpener, a casing having an outwardly directed bearing portion, a motor mounted within said casing, said motor having an armature shaft extending outwardly of said casing through said bearing portion, a driving gear secured to the outwardly extending end of said armature shaft for rotation therewith, said driving gear meshing with oppositely disposed driven gears, a shaft fixed to each of said driven gears for rotation therewith, a sharpener element fixed to each of said driven gear shafts for rotation therewith, an internal gear meshing with said driven gear and fixed relative to said casing, and a housing member enclosing said gears and sealing said gears from the entrance of dirt from said sharpener elements, said housing member having an annular bearing portion engaging the outer surface of said upstanding bearing portion and having another annular bearing portion engaging said casing.

4. In a pencil sharpener, a casing, a motor mounted within said casing, said motor having an armature shaft extending outwardly of said casing, a driving gear secured to the outwardly extending end of said armature shaft for rotation therewith, said driving gear meshing with oppositely disposed driven gears, a shaft fixed to each of said driven gears for rotation therewith, a sharpener element fixed to each of said driven gear shafts for rotation therewith, an internal gear meshing with said driven gears and fixed relative to said casing, and annular members mounted adjacent the bases of said sharpener elements, one of said annular members being of

greater diameter than the other annular member and extending under both of said sharpener elements.

5. In a pencil sharpener, a pair of rotatable sharpener elements, a supporting means for said elements, means for rotating said elements, an-

nular members mounted adjacent the bases of said sharpener elements, one of said annular members being of greater diameter than the other annular member and extending under both of said sharpener elements.

KENNETH R. BLAKE.
